UNITED STATES PATENT OFFICE.

SAMUEL SEGAL, OF NEW YORK, N. Y., ASSIGNOR TO BURGLAR PROOF LOCK AND HARDWARE CORPORATION, OF NEW YORK, N. Y., A CORPORATION OF NEW YORK.

LOCK.

1,212,823.

Specification of Letters Patent. Patented Jan. 16, 1917.

Application filed December 11, 1914. Serial No. 876,644.

To all whom it may concern:

Be it known that I, SAMUEL SEGAL, a citizen of the United States, and a resident of the city of New York, borough of Manhattan, in the county of New York and State of New York, have invented a new and Improved Lock, of which the following is a full, clear, and exact description.

This invention relates to builders' hardware and has particular reference to locks for doors or the like, and especially to locks which are so constructed as to resist efforts to open the same surreptitiously by force applied in any direction.

15 Among the objects of the invention, therefore, is to provide a lock construction including a keeper adapted to be secured preferably to the door frame and a lock casing carried by the door or other movable member, said casing carrying a movable bolt having one or more hooks or fingers slideable into interlocking engagement with portions of said keeper, the direction of movement of said fingers being transverse to the 25 longitudinal axis of the casing.

Another object of the invention is to improve the means for manipulating the bolt from either the inside or outside of the door, said means including a catch carried by the 30 bolt and serving to lock the same in either position of its movement, and independently movable actuators coöoperating with said bolt and catch.

The foregoing and many other objects of 35 the invention will hereinafter be more fully described and claimed and illustrated in the drawings forming a part of this specification, in which like characters of reference indicate corresponding parts in all the 40 views, and in which—

Figure 1 is a side elevation of the improvement complete shown in locked position on the inner side of a door; Fig. 2 is a horizontal longitudinal section substantially 45 on the broken line 2—2 of Fig. 3; Fig. 3 is a side elevation of the lock casing showing the bolt and controlling means for the bolt and also one of the actuators therefor, parts being in section on the line 3—3 of Fig. 5; Fig. 4 is a view similar to Fig. 3 but indicating the bolt in a changed position with parts in section on the line 3—4 of Fig. 5, the other actuator being shown; Fig. 5 is a

vertical transverse section on the line 5—5 of Fig. 2; and Fig. 6 is a detail view of the 55 bolt detached.

The several parts of this device may be made of any suitable materials, and the relative sizes and proportions, as well as the general design of the mechanism, may be 60 varied to a considerable extent without departing from the spirit of the invention hereinafter more fully described and specifically claimed.

Referring more particularly to the drawings, I show at 10 a portion of a door frame to which is secured a strong rigid keeper 11 having one or more ears 12 extending from the main portion of the keeper in planes perpendicular to the door frame, each ear 70 having an eye 13 parallel to the door frame. I show herein a keeper having two ears and with their eyes arranged coaxially, but as to this, as in other details, I do not wish to be unnecessarily limited. 75

At 14 I show a door coöoperating in closed position with the frame 10 and carrying on its inner face a lock casing 15. Formed on or carried by the outer end of the casing are a plurality of substantially U-shaped 80 guards 16, 17 and 18, the arrangement being such that when the door is closed a pair of these guards lie on opposite sides of one of the keeper ears 12. The space between each pair of these guards is wide enough to receive such ear freely and to provide for a slight sagging of the door or any other irregularity without interfering with the free opening or closing movement of the door. The center of curvature of the several 85 guards aligns with the axes of the eyes 13 of the ears when the door is closed.

The peculiar form of bolt 19 shown in detail in Fig. 6 is carried within the casing 15 and is movable within the casing in lines 95 transverse to the longitudinal axis of the casing for locking or unlocking purposes. The outer end of the bolt includes a plurality of fingers or hooks 20 housed within the guards aforesaid, the ends of the hooks 100 being adapted to span the spaces between adjacent guards and pass entirely through the eyes of the keeper ears when the bolt is in locking position. In this position the extreme end of a hook projecting from one 105 guard reaches into the interior of an adja-

cent guard as shown in dotted lines in Fig. 4. In this position, with the hooks extending through the ears of the keeper, there is no possibility for the lock to be sprung or the door to be opened by the use of a jinny or otherwise because the interlocking co-operation between the keepers and the hooks resists any relative movement between the keeper and the bolt mechanism.

10 Any suitable means may be provided to manipulate the bolt so as to cause the hooks thereof to open or close the spaces between adjacent guards. As shown herein I prefer to make the bolt with a substantially flat body movable in a plane parallel to the fixed wall of the casing 15, said bolt being formed preferably with a pair of ribs 21 and 22 on opposite faces of the bolt and co-operating respectively with shoulders 23 and 24 of the casing whereby the bolt as shown herein is limited in its movements in lines parallel to the door frame and transverse to the axis of the casing. In other words, the bolt is adapted to slide in a plane parallel to the inner face of the door and in a direction longitudinally of the door stile. The co-operating ribs and shoulders provide for long bearing points for the bolt, insuring that the bolt will move freely and 30 reliably without binding or cramping.

The flat shank 25 of the bolt is provided at its inner end with a pair of spaced lugs 26 having substantially twice the depth of the thickness of the shank 25 as shown best in Fig. 2. A stud 27 is secured to the face of the shank 25 inwardly from the lugs 26 far enough to accommodate a movable catch 28. The catch is pivoted at one end at 28^a to the extension 29 of the bolt and 40 has a finger 30 projecting longitudinally and thence laterally between the lugs 26. The square space between the lugs 26 provides a notch, the bottom of which serves to limit the swing of the catch toward the stud 27. Except for other features, the outward swinging movement of the catch will be limited by those parts of the lugs which project laterally from the main portion of the shank 25. A spring 31 is anchored in 50 the pivoted end of the catch and tends by co-operation with the stud 27 to hold the catch in the full line position shown in Figs. 3 and 4. The pivotal connection between the catch and the shank extension 29 is preferably by way of a pin formed on or secured to the catch and extends into a socket 29^a formed in the extension. By hooking the spring 31 beneath the head of the stud 27, the tendency for the catch to become displaced is prevented in a simple and practical manner.

The extension 29 has a toe 29^a which strikes against a lug 32 formed on the interior of the casing and thereby limiting 65 the movement of the bolt in open position,

as shown in Fig. 3. The shank has a heel 33 on the opposite side from the toe adapted to abut against another fixed stop 34 in the opposite side of the casing when the bolt is shifted to the closed position as shown 70 in Fig. 4. In other words, the bolt slides along the shoulders 23 and 24 between the limit stops or lugs 32 and 34. The hooks 20 also glide along the inner walls of the U-shaped guards during such movements of 75 the bolt. The catch has on its edge, remote from the hooks 20, a lug 35 which engages directly with a post 36 carried by the inner surface of the main wall of the casing and to which the opposite wall or plate 37 of 80 the casing is adapted to be secured, the outer edge 38 of the plate 37 bearing against the outer wall of the shoulder 24. The side of the post next to the catch is preferably flat and provided with square corners, and 85 the width of the post plus the length of the lug 35 is substantially equal to the throw of the bolt. By comparing Figs. 3 and 4 it will be observed that in the locking position of the bolt the lug 35 hooks over one 90 of the shoulders of the post 36 normally preventing the unlocking movement of the bolt, but in the open position of the lock the opposite end of the lug 35 abuts against the opposite shoulder of the post thereby 95 preventing the accidental movement of the bolt to locking position.

Any suitable type of actuator may be used to release the catch from the post and slide the bolt in either direction. Referring to 100 Figs. 2 and 3 I show a knob 37 journaled in a hub 38 on the main wall of the casing and rigidly secured to the inner end of the shank 39 of the knob is an actuator 40 having a pair of diametrically oppositely extending fingers 41 preferably of equal form and length and adapted to sweep around close to the inner surface of the main wall of the casing upon turning the knob in either direction. To the actuator 40 are connected a pair of pins 42. A pair of springs 43, the main portions of which are parallel to each other, extend beneath the heads of said pins 42 and tend to hold the actuator 40 with its fingers in a direction parallel to 110 the direction of movement of the bolt or in such position that the fingers 41 are normally well out of the way of the lugs 26. The springs 43 are anchored in any suitable manner to the casing as upon a stud 44. The 120 structure of the pins 42 is such that while the knob and its actuator may rotate freely in the bearing afforded by the hub 38, the springs are always retained beneath the heads of the pins and serve to restore the 125 actuator to the position shown after the actuator is turned far enough for its purpose in throwing the bolt. In other words, as soon as the actuator passes the dead center or the line at right angles to its normal 130

position, the force of the springs bearing upon both of the pins will complete the movement or half rotation of the actuator. Looking again at Fig. 3, the rotation of the actuator in a clockwise direction will cause the uppermost finger 41 to pass the first lug 26 and striking against the finger 30 of the catch will swing the catch far enough on its pivot against the force of the spring 31 to throw the lug 35 out of engagement with the post 36. The continued movement of the actuator in this direction will then cause the same finger 41 to strike the second lug 26 causing the bolt to slide to locking position as shown in Fig. 4, and the actuator at such time will have passed the dead center leaving it free to be rotated through the remainder of the half circle or in such position as to essentially result in the change of positions of the fingers 41 from the initial position. As soon as the bolt is moved to locking position and the active actuator finger passes out of the way of the finger 30, the lug 35 snaps into place behind the post 36 as shown in Fig. 4, insuring that the bolt will thus remain in locking position until the catch is again released by proper provided means. The movement of the knob and actuator just described pertains to the locking action by a person inside of the building. If the lock is to be unlocked by the same means, a counter-clockwise movement of the actuator 40 will cause the same finger to retrace its path, first throwing the catch and subsequently acting upon the uppermost lug 26, throwing the bolt until it is stopped by the stop lug 32 where it will be held by the catch as above described and allowing the actuator to return under the force of the springs 43 to the initial position.

For the operation of the bolt by an authorized person on the outside of the building, I provide a lock cylinder 45 anchored by means of bolts 46 to the casing plate 37 and with its axis coinciding with the axis of the knob and its actuator. The cylinder is controlled by means of a key and includes a stem 47 extending through the plate 37 and into the hollow interior of the knob 37. A second actuator 48 is journaled for rotation in the plate 37 and is adapted to be rotated by the stem 47 under the control of the key indicated at 49. The length of the stem is sufficient to compensate for any suitable adjustment of the cylinder with respect to varying thicknesses of door stiles and still maintain its operative connection with the actuator 48. The actuator 48 is provided preferably with but one finger 50 which sweeps around within the casing in a plane parallel to the plane of the actuator fingers 41 and cooperates with the lugs 26 and catch finger 30 in practically the same manner as above set forth. The depth of the lugs 26

and the finger 30 insures ample contact therewith by either actuator. In the usual type of lock cylinder, the key must be rotated through a complete circle so that it may be withdrawn after the locking or unlocking operation, and the finger 50, as indicated in Fig. 5, projects downwardly in the plane of the key shank in normal position or in such position as will allow the key to slip in or out of the cylinder; hence the finger 50 stands normally in a position so as not to interfere with the operation of the fingers 41 when the lock bolt is to be actuated by the knob on the inside of the door. It will now be appreciated why I provide two fingers 41 arranged as above set forth. For example, under ordinary conditions a rotation of the knob through a half circle is sufficient to throw the bolt in either direction, and if the bolt is thrown in one direction by a finger 41 and subsequently in the other direction by the key operated actuator finger 50, that finger 41 which threw the bolt in the first direction, but for the presence of the other finger 41, would have to be thrown around through an angle of 360 degrees to again actuate the bolt. As shown, however, even though the bolt be actuated in either direction by the key, one of the fingers 41 will always be in position to make a direct contact with the bolt mechanism to throw the bolt and with an operation of the actuator 40 through only 180 degrees.

I claim:

1. In a lock, the combination with a keeper, a casing, a bolt slidable transversely of the longer axis of the casing, said bolt having a hook interlocking with said keeper, a guide flange carried by said bolt on one side thereof toward the end, a second guide flange carried by said bolt on the opposite side thereof near the other end, parallel guide flanges carried by said casing and arranged to be engaged by the guide flanges on said bolt for guiding the bolt in its movement, a catch pivoted to said bolt on the opposite side of the bolt from said last named flange, means carried by the casing and arranged to be engaged by the pivoted catch for maintaining the bolt in its shifted position, and means for simultaneously releasing the catch and for shifting the bolt in a direction parallel with the guide flanges.

2. In a lock, the combination with a keeper, a casing, a bolt slidable transversely of the longer axis of the casing, said bolt having a hook interlocking with said keeper, the body portion of the bolt being substantially of the same width as that of the casing, a guide flange on one side of said bolt, a guide flange carried by the casing and arranged to cooperate with the guide flange on the bolt, said bolt having a flat shank provided with a guide flange, a second guide

- flange carried by said casing and arranged to be engaged by the last named guide flange on the shank, a pivoted catch carried on one side of said shank between the latter and the casing, a stop pin carried by the shank on the same side thereof, a spring for placing said catch under tension, one end of the spring bearing against said stop pin, lugs carried by said casing and arranged to be engaged by said catch for holding the bolt in its shifted positions, and means for releasing the catch from the lugs and for simultaneously forcing the bolt in a direction parallel to the guide flanges.
- 15 3. In a lock, the combination with a keeper, a casing, a bolt slideable transversely of the longer axis of the casing, said bolt having a hook interlocking with said keeper, the body portion of the bolt being substantially of the same width as that of the casing, a guide flange on one side of said bolt, a guide flange carried by the casing and arranged to coöperate with the guide flange on the bolt, said bolt having a flat shank 55 provided with a guide flange, a second guide flange carried by said casing and arranged to be engaged by the last named guide flange on the shank, a pivoted catch carried on one side of said shank between the latter and the casing, a stop pin carried by the shank on the same side thereof, a spring for placing said catch under tension, one end of the spring bearing against said stop pin, lugs carried by said casing and arranged to be engaged by said catch for holding the bolt in shifted positions, means for releasing the catch from the lugs for simultaneously forcing the bolt in a direction parallel to the 60 guide flanges, said last named means comprising a pair of lugs carried by said bolt, an extension carried by said catch disposed between said lugs in the locking position of the catch, a pair of pivoted actuators, each 65 actuator having fingers adapted to engage said catch extension for releasing the catch and for engaging one of the lugs of the bolt to move the latter with the pivoted axis of said spring catch.
- 70 4. In a lock, the combination with a keeper, a casing, a bolt slideable transversely of the longer axis of the casing, said bolt having a hook interlocking with said keeper, the body portion of the bolt being substantially of the same width as that of the casing, a guide flange on one side of said bolt, a guide flange carried by the casing and arranged to coöperate with the guide flange on the bolt, said bolt having a flat shank 75 provided with a guide flange, a second guide flange carried by said casing and arranged to be engaged by the last named guide flange on the shank, a pivoted catch carried on one side of said shank between the latter and the casing, a stop pin carried by the shank on the same side thereof, a spring for placing said catch under tension, one end of the spring bearing against said stop pin, lugs carried by said casing and arranged to be engaged by said catch for holding the bolt in shifted positions, means for releasing the catch from the lugs for simultaneously forcing the bolt in a direction parallel to the 80 guide flanges, said last named means comprising a pair of lugs carried by said bolt, an extension carried by said catch disposed between said lugs in the locking position of the catch, a pair of pivoted actuators, each actuator having fingers adapted to engage said catch extension for releasing the catch and for engaging one of the lugs of the bolt to move the latter with the pivoted axis of said spring catch.

In testimony whereof I have signed my name to this specification in the presence of two subscribing witnesses.
